TUBING CATCHER

William R. Guiberson, Dallas, Tex., assignor to
The Guiberson Corporation, Dallas, Tex., a corporation of Delaware

Application September 4, 1931, Serial No. 561,153

1 Claim. (Cl. 103—219)

This invention relates to new and useful improvements in tubing catchers.

In the use of tubing catchers it is very desirable to have a minimum clearance between the teeth of the catcher and the inner surface of the casing, when said teeth are in their lower or retracted position. This is done so that the slips will grip the casing after a slight fall of the tubing, thus making for quick action and preventing a long fall.

A large number of oil wells are extremely crooked, which is due to drilling with a rotary rig through hard or stony formations. The casing is frequently bent and caused to stand in distorted shapes and so much so that often the ordinary catcher owing to length can not be lowered in the casing.

One object of the invention is to provide a tubing catcher which will have a minimum length, thus permitting it to be used in crooked holes when other catchers can not be used.

Another object of the invention is to provide a short, stout and substantial catcher in which the movable parts will be more closely related, thus reducing the shimmyming or jiggling of the slips when the catcher is raised and lowered in the well.

A further object of the invention is to provide means for rigidly supporting the weight, whereby it will be held against unintentional movement when being lowered in the well or raised therefrom, thus eliminating shimmyming or jiggling which cause the slips to accidentally grip the casing.

35 A construction designed to carry out the invention will be hereinafter described together with other features of the invention.

The invention will be more readily understood from a reading of the following specification and 40 by reference to the accompanying drawings in which an example of the invention is shown, and wherein:

Figure 1 is a plan view of a tubing catcher constructed in accordance with the invention,

45 Figure 2 is an elevation of the same,

Figure 3 is a horizontal cross-sectional view taken on the line 3—3 of Figure 2,

Figure 4 is an enlarged horizontal cross-sectional view taken on the line 4—4 of Figure 2,

50 and

Figure 5 is an enlarged vertical sectional view of a portion of the catcher.

In the drawings the numeral 10 designates a central tubular support or mandrel having an upper coupling collar 11 at its top and a lower cou-

pling collar 12 at its bottom. A head 13 is fastened on the mandrel with its upper end adjacent the collar 11.

The head is shrunk or otherwise secured on the mandrel, but the invention is not to be limited to this structure. A plurality of radial wings or bosses 14 extend vertically of the head and are equally spaced to form fluid channels 15 therebetween. Each wing has an upwardly inclined overhanging guide face 16 along the center of which is formed a retaining rib or key 17, dovetailed in cross-section.

Upon each guide face is mounted a gripper slip 18 having its outer surface curved to conform to the arc of the casing to be gripped and provided with transverse teeth 19, beveled to trip upon a downward thrust. Each slip is slidable on its guide face and has a central upright groove 20 receiving and complementary to the key 17, whereby the slip is held against outward displacement from the face 16.

A winged guide 21 is suitably fastened on the mandrel just above the collar 12 and includes a notched flange 22. The wings of the guide and the notches of the flange permitting a free passage of fluids. The annular skirt 24 of a cylindrical weight 25 rests upon the flange 22. A coiled spring 23 surrounding the mandrel is partially compressed by the weight and positioned within said weight. The lower edge of the skirt 24 may have notches 24' for the escape of sand and the like.

The weight has its upper edge beveled to offer less resistance and is provided with spaced ears 26 in which the lower ends of short links 27 are pivoted. The upper ends of these links are pivoted between ears 28 on the bottoms of the slips 18. The weight having a solid foundation on the flange firmly supports the slips by means of the links 27. The spring is held under such tension by the weight as to make the catcher very quick acting.

The upper ends of the keys 17 have rounded guide bosses 29 which with the wings of the guide 21 protect the slips and weight from contact with the casing when the parts are inactive. By this arrangement the catcher may be freely raised and lowered in the casing without catching therein. The close coupled weight and spring cuts down the length of the catcher and will permit its use in crooked holes. The weight resting on a firm foundation prevents any shimmyming or jiggling while the catcher is being raised from the well or lowered into it. The short links 27 and the weight resting on the said flange does away with

the abutting shoulders common to other catchers at the bottom of the guide faces 16. The slips are of standard length but the faces 16 may be shorter and more inclined (this catcher being designed 5 for the lighter loads).

In using the catcher it is connected in the well tubing (not shown) by means of the collars 11 and 12, just above the working barrel or at any other point desired. So long as the tubing is 10 raised and lowered under normal conditions the parts remain inactive. Should the tubing be dropped or break at any point above the catcher the latter will automatically set the slips 18 and quickly catch the tubing without damage or dangerous length of fall.

When the tubing falls the weight 25 owing to its inertia and the tendency of the spring 23 to expand, remains relatively stationary to the mandrel 10 which falls faster than said weight. The 20 slips 18 being supported by the weight will be spread by the head 13 which falls with the mandrel. The inclined faces 16 cause the slips to expand radially, whereby their teeth 19 grip the

casing (not shown). The action takes place so rapidly that the catch is made within a few inches.

Various changes in the size and shape of the 80 different parts, as well as modifications and alterations, may be made within the scope of the appended claim.

What I claim, is:

In a tubing catcher, an axial support, a head 85 fastened on the support and having inclined guide faces, slips mounted on the guide faces, a weight slideable on the support, short links pivotally connecting the slips and the weight, whereby the said slips and weight are closely coupled, a coiled spring mounted on the support and partially compressed by the weight, a guide secured on the support immediately below the spring carrying means, the head and the guide engaging the casing and holding the weight and slips out of contact therewith, the weight being rigidly carried by 90 the guide.

WILLIAM R. GUIBERSON.
